SLIDING DOOR

Francis Helbert, Boulogne sur Seine, and Henri
Jules Peignen, Maisons Alfort, France

Application February 27, 1951, Serial No. 212,927

Claims priority, application France March 7, 1950

4 Claims. (Cl. 160—232)

1

This invention generally relates to sliding doors, of the type expandable and retractable over a path which may be at least in part arcuate, and more specifically it relates to such a sliding door having smooth and deformable sides, and adapted for use as a closure means for premises and enclosures of various types, articles of furniture such as cabinets, and particularly elevator shafts.

It is an object of the invention to provide a sliding door of the above-described type arranged for expansion and retraction over a pair of parallel guide-ways at least in part arcuate, which comprises a plurality of adjacent elements extending across said guide-ways generally normally thereto, rotational means between the adjacent elements and guiding or rolling means arranged at, at least, one end of the elements and cooperating with said guide-ways, each element being rotatable by a predetermined angular amount about the said rotational means relatively to the adjacent element, whereby the sliding door may be expanded along an arcuate path and retracted within a comparatively small space.

A further object is to provide a sliding-door of the type just specified wherein the said elements are panels mounted on supports, the afore-mentioned rotational means between adjacent elements being provided by hinges secured to the said supports and serving both as the connecting means and the pivoting means for the said elements relatively to one another.

It is a yet further object of the invention to provide such a sliding door wherein safety means are provided between the adjacent elements for averting the risk of the user's fingers being inadvertently pinched between the adjacent elements.

In a preferred embodiment of the invention, the safety-means comprise channels extending substantially throughout the length of the elements at the ends thereof, said channels being mounted in alternately reversed positions and so disposed relatively to the rotational means that, during the rotational movement of any one element relatively to its adjacent element and throughout the full extent or amplitude of such movement, the outer edge or flange of the channel on each element will remain inside the channel of the adjacent element.

To provide a clearer understanding of the invention, some exemplary embodiments thereof will now be described by way of indication and not of limitation, reference being had to the accompanying drawings wherein:

Fig. 1 is a diagrammatic perspective view of a sliding door according to the invention;

Fig. 2 is a fragmentary view thereof in elevation;

2

Fig. 3 is a corresponding view in cross-section on line III—III of Fig. 2;

Fig. 4 is a corresponding view in horizontal section on line IV—IV of Fig. 2;

Fig. 5 is an exploded perspective view on an enlarged scale showing the interconnecting means between the elements of the sliding door assembly and the guide means therefor;

Figs. 6 and 7 are fragmentary detail views in horizontal section, showing the positions assumed by adjacent elements and their interconnecting means, respectively in a straight and an arcuate portion of the path;

Fig. 8 is a cross section of a modification, on line VIII—VIII of Fig. 9;

Fig. 9 is a corresponding horizontal section on the lines IX_a—IX_a, IX_b—IX_b, IX_c—IX_c, of Fig. 8;

Fig. 10 is a perspective view, on an enlarged scale, of a detail of the construction shown in Figs. 8 and 9; and

Fig. 11 is a view similar to Fig. 9 but relating to a further alternative.

As shown in Figs. 1 to 7, a sliding door according to this invention comprises a series of adjacent elements each consisting of a pair of strips 1 which may be made of rolled sheet metal, or any other suitable material, such as wood, with or without metal element affixed thereto. The strips 1 are secured two by two to spacer cross-members or braces 2, as by screws, rivets, or other suitable connecting means to be supported thereby in box-like relationship (cf. Fig. 4).

The strips 1 are shown as having one edge thereof bent to the form of a polygonal flange. Alternatively however the flange might be rolled to the form of a 90°-arc with an appropriate radius. Such an arrangement is eminently suitable for the provision of a smooth surface of the kind required for example in connection with elevator-shaft sliding doors. For other purposes however, a different contour may be selected for the strips 1, e. g. they may be ribbed or formed to any other appropriate design.

The spaced strips 1 comprising a common element are similar in length and are offset relatively to each other in the direction of the door's motion, by a suitable distance to make allowance for the relative rotation of the elements, as later described.

A number of the spacer 2 (Fig. 5) are provided with hinge sockets 3 which constitute both the connecting and interpivoting means for the elements relatively to one another.

The hinge-pins 4 of the upper hinge assemblies are supported on the lugs 5 forming stops, and receive bushings 6 at their tops, being pinned therein by means of cotters 7. The bushings 6 support rollers 8 horizontally journaled on arms

projecting upwardly therefrom, the rollers serving to support the door while allowing it to move as the rollers run on the runway 9 rigidly connected to the securing members 10 to the wall 11 in which the door is installed.

The hinge-pins 4 for the lower hinges, supported on the stop-lugs 5 receive the rollers-supporting bushings 12 carrying the vertically-journalled rollers 13 which project into a runway groove 14 formed in the floor to guide each element in its displacements. The rollers 8 and 13 are desirably provided with a suitable coating material, such as "Nylon" or the like effective to impart a very smooth operation to the sliding door.

It will be understood that the running rollers and the guiding rollers described above may be reversed in position, i. e. the bushings and rollers 6 and 8 and rails 9 may be arranged at the bottom while the guide rollers with their supports 12 and 13 and the guide-way 14 would then be provided on top.

The sliding door includes a suitable number of elements 1 identical to those just described, interpivoted by the hinges 3. The end elements 15 however are provided with a special arrangement now to be described (see Figs. 2 to 4). The said end elements 15 are fitted with spacer members 17 which terminate, at the end remote from the hinge, in an end flange bent back at right angles to seal the space between the strips and provide the end-wall of the door, and the end strip 18 itself also has a special configuration, in that it is formed with a bent flange 19 adapted to overlap the normally-formed flange 20 of the opposite strip 21 of the pair.

Moreover, each end element such as 15 is provided at its top with a bracket 22 having a running roller 23 journalled on it, and at its base with a support 24 formed with a guide roller 25, the bracket 22 and support 24 being each mounted on a transverse arm formed on the upper and lower spacer members 17, respectively (see Fig. 2 and 4).

In instances where the sliding door is to be mechanically actuated, the end element which is to have the operating cable attached to it may be provided with an additional upper roller 26 serving to reinforce the point of cable attachment, which is the bracket of the running rollers.

For this purpose, the rollers 22-26 may, as shown, be mounted on a common bracket 27 mounted on pins 28-29 welded to the spacer. The end element 15 thus in effect comprises three running rollers. It will be understood that with this construction, the end element 15 should not have to travel over an arcuate portion of the path of the sliding door in order to avoid jamming.

A remarkable feature of the sliding door described consists in the fact that it may be mounted in the opening of a flat wall in such a way that the surface of the door is flush with the inner surface of the wall, and that there will be no break between the door and the wall other than a narrow gap 30, 31 (Figs. 2 and 3) respectively at the top and bottom of the door.

This feature is made possible owing to the fact that the rails 9 are mounted just above the opening in the wall 11 and supported from the said wall (see Fig. 3), so that a substantially unbroken smooth surface between the wall and the door may be obtained.

At the bottom, the unbroken surface between

the door and the wall is provided by the guide means itself, as shown in Fig. 2.

Fig. 6 and 7 illustrate the manner in which the elements of the sliding door described are able to negotiate a curve. As shown, the centre 39 of the hinge is so predetermined that the tip 40 of the flange of the element on the left rides within the recess 41 defined in the adjacent element as the last-mentioned element is rotated relatively to the other element in the direction of the arrow 42. The maximum amplitude of such relative rotation is defined by the angle 43 (Fig. 6) which is such that it brings the edge 44 into engagement with the surface of the element 1. At the same time, the opposite edge 45 is opened out on the other side of the door.

While a rotation in the reverse direction is possible, it will be noted in Figs. 6 and 7 that the centre of the hinge does not lie in the centre plane of the elements, so that the angle of rotation of the elements is larger towards the side nearest to the said centre; thus the angle 43 is greater than the angle 46. Conversely, the minimum radius of the curves negotiable by the elements is smaller. For example, in the case of elements 200 mm. in length and 50 mm. thick, the minimum radius of the curves practicable with the construction of Figs. 4 and 6 is 100 mm. on the side of arrow 46 and 175 mm. on the side of arrow 47. If the hinge centres were made to extend on the centre plane of the elements, the maximum angles of rotation of the elements would obviously be the same in either direction, but the minimum radius of curvature achievable would necessarily be greater than the smaller one of the two above indicated values. Thus with the same dimensions as above, the said radius would be 130 mm.

The above discussion will show how the position of the centres of the hinges may be geometrically predetermined on the elements in order to provide a desired radius of curvature towards each side of the door.

The sliding door construction described possesses excellent characteristics of strength and air-tightness, owing to the rigidity of its component parts. Each box-shaped element may, moreover, be filled with a suitable insulating, fire-proofing, or other material. A further advantage of this construction is that the door is easily manufactured without requiring special tooling, its component elements being readily producible with the usual machinery found in metal sheet-forming and lock-smiths' shops. Moreover, the said components are interchangeable among sliding doors of a given common height dimension, a considerable advantage in quantity production, as well as for maintenance and repair. Besides, the fact that the strips 1 are identical, at least as far as the intermediate strips are concerned, makes for great facility in supply both for stock and for production, thus greatly reducing the cost price.

In the modified construction shown in Figs. 8 to 10, means are further provided to prevent the users' fingers from being accidentally caught in between adjacent interpivoted elements.

In one exemplary embodiment of an improved sliding door according to this modification of the invention, illustrated in Figs. 8 to 10, the door is made up of two sets of panels P₁, P₂ in alternating relationship, only three of which are shown in Fig. 9. Each panel P₂ consists of a plate 51 which may be e. g. a stamped metal sheet or a strip of wood. The plate 51 is formed

or provided at each end with an arcuate flange 52 preferably metallic. A further plate 53 secured in parallel spaced relation to the plate 51 defines a box-like structure therewith and is formed with end flanges bent inwards in the shape of a concave or reentrant curve 54 followed by a flat portion 55 followed in turn by a flange 56 bent outwards at right angles thereto and secured as by welding or riveting to the plate 51.

The complementary panel P1 comprises a plate 57, such as a metal stamping, strip of wood, or the like, provided at each end with a convex arcuate flange 58 greater in angular extent than the portion 52, and a further and similar plate 59 is secured in parallel spaced relationship with the plate 57 to provide a box-shaped structure therewith.

The above-described panels P1 and P2 are interpivoted in a manner generally similar to that described in connection with the previous embodiments of the invention shown in Figs. 1 to 7, through the medium of hinge assemblies illustrated in detail in Fig. 8. In the construction shown in that figure, the pivotal connection is provided by means of an upper supporting or carrier hinge structure A, an intermediate hinge structure B and a lower, guiding, hinge structure C.

The upper, carrier flange A (Fig. 10) comprises a rolled sheet or strip 59 secured to the plate 57, a pivot pin 60 inserted thereinto, and a bushing 61 secured by a screw 62 to the strip 63 of the complementary panel P1. The pivot 60 carries a supporting bracket 64 for a roller 65 running on a rail 66. The pin is retained in position by a ring 67 pinned thereon with an interposed ball-thrust bearing 68.

The panel P1 is suspended from the rail 66 by a pair of carrier hinge structures similar to that just described, while the panels P2 are supported on the bushings 61. The female part of the intermediate hinge B comprises a rolled strip 69 rigidly assembled to the complementary sheet 61.

The lowermost, guiding, hinge C comprises a pin 70 formed at its lower end with a guide roller 71 engaging a runway 72.

It will be noted that the supporting bracket of the carrier roller is rotatable with respect to the uppermost hinge assembly to enable the requisite pivoting and sliding movements in curves.

The operation of this sliding-door construction is similar to that previously described in connection with Figs. 1 to 7. However, during such operation, the flanges of the overlapping elements remain substantially spaced by a constant distance, thus averting any danger of pinching one's fingers and similar mishaps. Moreover, the arrangement used for suspending the panels P1 including the carrier hinges A with the panels P2 provided with pivotal means such as the bushings 61, which are supported rather than supporting elements, is advantageous in that any vertical play and/or excess thickness in the pivotal connections which may in some cases occur, will not be cumulative.

In a somewhat modified construction of the sliding door (Fig. 11) each panel P3 is identical with the adjacent panels, and acts as a supporting element on one side and a supported element on the other.

Such panel is made from a metal strip 73 having the configuration shown with an arcuate end flange 74 and a further strip 75 parallel spaced

from the first and differing therefrom only in the greater extent of its arcuate end flange 76.

One (e. g. the right) edge of panel P3 is rigid with a rolled socket member 59 receiving the pivot pin 60, while its other or left edge removably carries a bearing 61 inserted, prior to assembly, over the pin 60 of the adjacent panel.

It will be understood that the invention is in no way restricted to the details of embodiment illustrated and described, but extends its scope to cover any operative modifications in the various constituent parts thereof. Thus, in particular the panels may be made from any suitable materials; the sliding door may be mounted for horizontal, vertical, or any desired angular displacement. Other modifications will appear to those familiar with the art within the scope of the ensuing claims.

What we claim is:

1. In a sliding door for use with a pair of parallel spaced guide-ways arcuate over at least part of their length, a plurality of like panels extending between said guide-ways, guide means carried by at least one end of at least some of said panels adapted to cooperate with at least one of said guide-ways, each of said panels comprising two spaced parallel faces and edge portions connecting said faces, hinge means including cooperating hinge members respectively carried by adjacent panels and pivotally interconnecting said panels in edge-to-edge relationship, said hinge means being disposed between the planes of opposite faces of the respective panels, a lateral extension on one face of each of said panels forming a smooth continuation of said face, a similar but oppositely directed lateral extension on the opposite face of the adjacent panel defining with the first mentioned extension and the corresponding edges of said panels a recess extending throughout the height of the panels, said hinge means being confined within said recesses, said extensions having cooperating inwardly bent end portions extending into said recesses to prevent opening of said recesses and exposure of said hinge means during articulation of said panel structures as said sliding door is moved along said guide-ways.

2. The sliding door of claim 1 wherein the axis of said hinge means is positioned substantially mid-way between the inner faces of said lateral extensions of two adjacent panels.

3. The sliding door of claim 1 wherein said inwardly bent end portions of said lateral extensions of said panels have an arcuate shape co-axial with said adjacent hinge means.

4. The sliding door of claim 1 wherein said edges of said panels are at least partially in the form of a portion of a cylinder co-axial with said adjacent hinge means.
